UNITED STATES PATENT OFFICE.

JOHN B. CLANTON, OF CHARLOTTE, NORTH CAROLINA.

HEAT DEFLECTOR.

Application filed January 15, 1923. Serial No. 612,692.

To all whom it may concern:

Be it known that I, JOHN B. CLANTON, a citizen of the United States, residing at Charlotte, in the county of Mecklenburg and 5 State of North Carolina, have invented a new and useful Heat Deflector, of which the following is a specification.

This invention has reference to radiator coils, and aims to provide a novel means to 10 be employed in connection with heating coils positioned in open fireplaces or the like, whereby the heat which usually passes off through the chimney of an open fireplace, may be retarded in its upward passage and 15 directed to the coils.

With the foregoing and other objects in view which will appear as the description proceeds, the invention resides in the combination and arrangement of parts and in the 20 details of construction hereinafter described and claimed, it being understood that changes in the precise embodiment of the invention herein disclosed, may be made within the scope of what is claimed, without 25 departing from the spirit of the invention.

Referring to the drawing:

Figure 1 is an elevational view disclosing heating coils supplied with a device constructed in accordance with the invention.

30 Figure 2 is a sectional view taken on line 2—2 of Figure 1.

Referring to the drawing in detail, the reference character 5 designates an open fireplace in which the coils 6 are arranged, 35 the coils being secured in any appropriate manner to the rear wall of the fireplace.

The coils 6 are in communication with the radiator 7, the communication between the coils 6 and radiator 7 being established 40 through the pipe 8, pipe 9 and pipe 10.

Radiators such as indicated at 11 may be in communication with the radiator 7, as through the feed pipe 12 and pipe 13. Water is supplied to the coils 6 from the 45 tank 14 which is in communication with the coils at the lower end thereof, as through the feed pipe 15.

The pipes 16 and 17 establish communication between pipes 12 and 15 and permit 50 condensation to pass from the pipes 10 and 13 to the pipe 15 and be returned to the tank, thereby eliminating the collection of

fluid in the radiators 7 and 11. Suitable water cocks indicated at 18 are disposed in the pipe 17 and have communication with the atmosphere, so that a person may readily observe the water level in the tank 14, it being obvious that the water in tank 14 will assume an equal level in pipe 17.

A suitable valve member indicated at 19 is provided for controlling the passage of fluid to the various pipes of the system. An exhaust valve is indicated at 20 and is in communication with the pipes 8 and 9 to allow the steam to exhaust when a predetermined pressure has been reached.

In order that the maximum amount of heat will contact with the coils 6, baffle plates 21 are provided, which plates are formed with arms 22 that have hook portions 23 designed to hook over one pipe of a coil and rest against the adjacent lower pipe of the coil thereby supporting the plate at an angle with respect to the coils to direct the heat to the coils.

From the foregoing it will be obvious that as the heat passes upwardly, the heat will collect under the baffles where the heat is forced against the coils to heat the fluid therein.

What is claimed as new is:

1. In a fireplace, a series of pipe coils positioned in the fireplace, deflectors, each deflector being suspended from a coil and resting on the adjacent lower coil, and said deflectors being supported at oblique angles with respect to the coils.

2. A heating device for use in connection with horizontally disposed heating coils comprising a body portion in the form of a plate, hook members including vertical arms secured to the body portion and adapted to support the body portion at an oblique angle with respect to the arms, said hook members adapted to be positioned over a coil, the arms adapted to extend downwardly to engage the adjacent lower pipe of the coils to hold the body portion in its active position.

In testimony that I claim the foregoing as my own, I have hereto affixed my signature.

JOHN B. CLANTON.
